UNITED STATES PATENT OFFICE.

RALPH I. ELLIOTT AND CARL E. LICHENS, OF BERKELEY, CALIFORNIA; SAID LICHENS
ASSIGNOR, BY DIRECT AND MESNE ASSIGNMENTS, OF HIS ENTIRE RIGHT TO ED-
WARD J. GINOCHIO, OF OAKLAND, CALIFORNIA.

SHARPENING DEVICE.

Application filed February 9, 1925. Serial No. 7,964.

Our invention is in a sharpening device for different types of cutlery, particularly for sharpening shears. The particular feature of the invention has to do with a simple 5 way of changing the bevel. In shears the bevel is flatter near their pivot than at the point, and with the old type of shear sharpener it was inconvenient to obtain the proper bevel. Our improvement is shown in 10 a specific adaptation to the swiveling bar type of sharpener in which the swiveling bar may also be given a longitudinal reciprocation, the cutting surface such as a file, or stone, being situated at the handle 15 end of the implement.

Our invention will be more clearly understood from the specification and drawings in which:

Figure 1 is a plan view of the assembled 20 device.

Figure 2 is a side elevation of Figure 1 in the direction of the arrow 2.

Figure 3 is a detail side elevation showing 25 our specific clamping yoke for forming a bevel, holding the tool in a position to cut a coarse bevel.

Figure 4 is a view similar to Figure 3 with the pivoted bearing plate swiveled upwardly in a position to cut a sharp bevel.

Figure 5 is an end elevation of the 30 perforated guide plate in the direction of the arrow 5 in Figure 1.

Figure 6 is a section on the line 6—6, of Fig. 7 in the direction of the arrows.

Figure 7 is a front elevation of Figure 6 35 illustrating in conjunction therewith a manner of holding the bearing plate and file to allow a manually controlled up and down oscillating movement to give a changing bevel, as required for shear blades and the like.

In the drawings the base 1 is preferably 40 formed T shaped with a shank 2 and cross piece 3, a perforated guide plate 4 extends upwardly from the rear end of the shank, and the clamping bracket 5 is sloped from the end of the cross piece 3, suitable apertures 6 being left in the cross piece for bolting to a work table. The clamping 45 bracket preferably extends the entire width of the cross piece 3, and has a co-acting clamp 7 operated by a screw threaded bolt 8 formed integral therewith, extending through an aperture 9 in the bracket. A

wing nut 10 bears on the flat surface 11 of 55 the lug 12 formed integral with the clamping bracket. The work 13 shown as a blade to be sharpened is clamped between the clamping bracket and the co-acting clamp 7, and thus by means of the wing nut 10 held 60 firmly in position.

The guide plate 4 has a series of perforations 17 at different elevations in the plate, and these perforations have rounded corners 18. A bar 19 extends through these perforations, and has a nut 20 at one end to limit its movement, and at the other end carries a yoke 21, with upper and lower arms 22 and 23. In the base 24 of the yoke a bearing plate 25 is pivoted by the pin 26' extending through an aperture in the base 24. A supporting screw 26 extends through the arm 23, and a clamp screw 27 through the arm 22. These have any suitable means for turning such as the screw driver slot 28 in 70 the screw 26, and the wing head 29 on the screw 27. A file 30 is clamped between the bearing plate and the clamp screw 27 and preferably has a handle 31. A sharpening stone may be substituted for the file. 80

The manner of operation of our sharpening device is as follows: If a constant bevel is required the implement would be set up to give the proper angle of cut on the blade 13 which may be the angle shown in Figs. 85 2, 3 and 4, or any other desired angle. The angle of cut may also be altered by inserting the bar 19 through different perforations 17. The file is then pressed down and reciprocated lengthwise of the blade until the 90 blade is sharpened. It may also be given a longitudinally reciprocating motion by shoving it in and out with the bar passing through apertures 17, or a combined swinging and reciprocating movement may be 95 given it, to produce a uniform bevel along the edge of the blade. It will be noted that the rounded corners 18 of the apertures 17 allow the bar 19 to pivot therein.

For sharpening shears the file may be set 100 first as shown in Fig. 3 and operated on the blade adjacent its pivot to give a flat bevel. The whole blade may be beveled at the same angle and later the outer part given a sharper bevel as shown in Figs. 2 and 4 by 105 swinging the bearing plate 25 upwardly, and thus clamping the file in a different position in relation to the work. An alter-

native manner of sharpening the shear would be to form the flat bevel near the pivot, as shown in Fig. 3, sharpen a small portion and as the file is worked towards the point of the shear gradually change the position by swinging the bearing plate 25 upwardly through operation of the screw 26 and the clamp screw 27. The end of the file bearing against the base 24 of the yoke gives sufficient cross bearing to prevent the file from turning about the screws as a pivot.

Our invention may be considerably modified to suit special circumstances or to operate on different types of blades without departing from the spirit thereof.

Referring particularly to Figures 6 and 7, the bar 19 supports a yoke 32 similar to the yoke 21, except that it has side faces 33 as well as the arms 22' and 23'. The bearing plate 25' is shown pivoted in the center on a journal 34 having screw threaded ends 35 with washers 36, nut 37 and lock nut 38 thereon. Through the arms there are threaded screws 26' and 27' similar to those of the construction in Figures 2, 3 and 4.

The file 30' is placed on the bearing plate and pressed downwardly thereon by a spring 39 bearing on a plate 40 on top of the file. A spring 41 presses upwardly from the lower arm on the base of the bearing plate 25'. If necessary the file is wedged between the faces 33 by shims 41 of wood or other suitable material. The screws 26' and 27' are preferably threaded into the arms so as not to contact with the bearing plate or the file, if a graduated bevel is desired.

The manner of operation is as follows: The nuts 37 and lock nut 38 would be clamped sufficiently tightly so that the bearing plate would have a stiff oscillating motion. The springs 39 and 41 securely hold the file and bearing plate in contact. The handle of the file is grasped and swung from side to side, drawing the file over the blade being operated on. Presuming this to be a blade of a shears, which at the base has a coarse bevel as shown in Figure 3, and at the points a sharp bevel as shown in Figure 4, the hand would be given such a motion as to not only swing the file from side to side but oscillate it up and down through the positions illustrated in Figures 3, 2 and 4. The springs will follow the motion of the bearing plate and file holding the file tightly in position, and with or without the aid of the clamp nuts 37 and 38 restrain the movement so that the hand may give a graduated motion across and up and down in relation to the blade being sharpened.

The operation requires a certain amount of mechanical skill which is easily acquired as the stroke of the hand is a straight line motion from a lower position at one side of the device to an upper position at the opposite side as illustrated in Figure 4, and it is

only necessary to move the hand backwards and forwards in substantially the same line for a few times until the blade is sharpened with the proper graduated bevel.

The construction of the graduated beveling sharpener of Figures 6 and 7 could be considerably altered, for instance, any way of clamping the file to the bearing plate would probably be satisfactory, so long as it allowed the bearing plate to oscillate on its axis up and down. Sufficient resistance or friction should be used to make the oscillating movement of the bearing plate somewhat stiff so the hand will have better control over the changing bevels as illustrated in Figures 2, 3 and 4.

Having described our invention, we claim:

1. A sharpening device comprising a frame, a bar pivotally mounted therein, and an abrading element having one end adjustably secured to the end of the bar, and its other end remote from said bar.

2. A sharpening device comprising a frame, a bar pivotally mounted therein, an abrading element having one end secured to the end of said bar, and means for adjusting the angle between said bar and said abrading element.

3. A sharpening device comprising a frame, a guide plate secured thereto and provided with a perforation, a bar mounted in said perforation to pivot and reciprocate therein, and an abrading element secured to said bar.

4. A sharpening device comprising a bar, a guide plate having a perforation adapted to receive said bar for pivotal and reciprocating movement therein, an abrading element secured to said bar, and means to adjust the relation between said bar and said abrading element.

5. A sharpening device comprising in combination a guide plate having a series of perforations at different elevations, a clamp for a blade, a rod extending through the perforations in the guide plate, and an abrading element connected to said rod, and means for adjusting the angle between said rod and said abrading element.

6. A sharpening tool as claimed in claim 5, in which the adjustable mounting for the abrading tool comprises a swiveling connection of the abrading tool and the rod such swiveling connecting being on the end of the rod.

7. In a sharpening device, a single fixed guide plate, apertures in the guide plate at different elevations, and a rod adapted to support an abrading tool said rod being mounted in any one of said apertures.

8. In a sharpening device, a single fixed guide plate, apertures in the guide plate at different elevations, and different positions laterally, and a rod adapted to support an

abrading tool said rod being mounted in any one of said apertures.

9. In a sharpening device a rod, a fixed yoke on the end of the rod, an adjustable mounting for an abrading tool in the yoke.

10. In a sharpening device a rod, a fixed yoke on the end of the rod, a horizontal support for a blade, and a vertical swivel in the yoke for an abrading tool.

10 11. In a sharpening device a rod, a yoke on the end of the rod, a bearing plate pivoted in the yoke to swivel in a vertical direction, a bearing screw to support the bearing plate in the desired position, and a clamp screw to clamp an abrading tool to the bearing plate.

12. A sharpening device comprising in combination a guide plate having a series of perforations at different elevations, a 20 clamp for a blade in substantially a horizontal position, a rod extending through any one of the perforations in the guide plate, a yoke on the end of the rod, a bearing plate pivoted in the yoke to swivel in a vertical direction, a bearing screw to support the bearing plate in the desired position, and a clamp screw to clamp an abrading tool to the bearing plate.

13. A sharpening device comprising in combination, a holder for an abrading tool, a clamp for a blade, means to allow transverse swivelling of an abrading tool, and means to allow up and down oscillation thereof, said oscillation being up and down relative to the point of swiveling, and the 35 abrading tool swiveling in a vertical plane.

14. A sharpening device comprising a

pivottally mounted rod, a fixed yoke secured to the end of said rod, a holder for an abrading tool mounted in said yoke and means to 40 allow said holder to have a free oscillating movement up and down.

15. A sharpening device as claimed in claim 14, in which the means for allowing the oscillating movement comprises springs 45 bearing on the abrading tool.

16. A sharpening device comprising a pivottally mounted rod, a yoke secured on said rod, side faces on the yoke, a holder pivottally mounted on the side faces, means 50 to hold an abrading tool on the bearing plate and clamp nuts to frictionally retard the oscillation of the bearing plate.

17. A sharpening device as claimed in claim 16, in which the means to hold the 55 abrading tool on the bearing plate comprises a spring bearing on the abrading tool.

18. A sharpening device comprising a pivottally mounted rod, a yoke secured on said rod, a bearing plate pivottally mounted 60 in the yoke, a spring pressing on the surface of the bearing plate, and a spring adapted to press on an abrading tool whereby said abrading tool has free oscillating movement to form a graduated bevel.

19. A sharpening device as claimed in claim 18, having in addition screws threaded through the yoke and engaging the bearing plate and abrading tool whereby the 70 abrading tool will give a fixed bevel.

In testimony whereof we affix our signatures.
